No. 636,799.

Patented Nov. 14, 1899.

H. HARBECKES.
WATER HEATER AND TANK.

(Application filed Feb. 18, 1899.)

(No Model.)

UNITED STATES PATENT OFFICE.

HENRY HARBECKES, OF PHILADELPHIA, PENNSYLVANIA.

WATER HEATER AND TANK.

SPECIFICATION forming part of Letters Patent No. 636,799, dated November 14, 1899.

Application filed February 18, 1899. Serial No. 706,037. (No model.)

To all whom it may concern:

Be it known that I, HENRY HARBECKES, a citizen of the United States, residing in the city and county of Philadelphia, State of Pennsylvania, have invented a new and useful improvement in Water Heaters and Tanks, which improvement is fully set forth in the following specification and accompanying drawings.

10 This invention relates to water-heaters; and it consists of a novel construction of tank and heating apparatus whereby the heat units are effectively utilized and the water expeditiously heated, a further object of the invention being to furnish a water-heater that can be connected with and operated by the usual range and stove or which can be disconnected therefrom and independently operated, provision being made by the employment 15 of a lower flattened water-heating chamber for positively causing an upward circulation in the pipe which leads therefrom through the center of the water-tank and a downward circulation through the outer portion of the 20 water-tank, a connection being made from the lower portion of said water-tank to the lower portion of said heating-chamber.

The invention further consists of the details of construction, all as will be hereinafter 30 fully set forth, and particularly pointed out in the claim.

Figure 1 represents a side elevation of a water-heater embodying my invention. Fig. 2 is a central vertical section thereof.

35 Similar letters of reference indicate corresponding parts in the drawings.

Referring to the drawings, A designates a water-tank mounted upon a stand B and having a central upright flue C and a water-supply pipe D. Situated below the tank A is a heating-chamber E, communicating with the lower end of said tank by means of a pipe F, leading from the side of the tank to the bottom of the chamber E, said heating-chamber 40 being preferably of a flattened shape and of considerable area as compared with the inlet-pipe F, whereby a comparatively thin body of water of considerable lateral or horizontal area is always exposed to the effect of the 45 heating medium. The chamber E also communicates with the upper end of the tank by means of a pipe G, leading from the upper

side of said chamber and passing through the flue C and connecting with the upper end of the tank. A service-pipe H leads from the 55 upper end of pipe G and may also be provided with a branch J for connection with the heating apparatus of a stove or range, although it is understood that the present water-heater can be used independently. The 60 pipe F may also have a branch K connecting with the heating apparatus of a stove or range, and a pipe L serves as means for draining the tank, heating-chamber, and water system.

A burner M, preferably for gas, is situated 65 below the chamber E to direct the flame against the lower side thereof, and a hood N covers and surrounds the chamber E to direct the passage of the heated gases from the burner. The top of the hood N is provided 70 with a central opening and a depending flange P, having openings Q. The flange rests upon the top of the chamber E, with the opening in the hood concentric with the flue C. The hood is preferably of metal, with an interior 75 lining R, of asbestos, and is situated close to the top and sides of the chamber E to direct the heated gases in intimate contact therewith.

The chamber E is provided with an interiorly-screw-threaded hub S at its top to receive the lower end of the pipe G, and in the bottom of the chamber is a larger opening T, having a bushing U, forming the union with pipe F. By removing said bushing it is obvious that the interior of the chamber can be cleaned as occasion may require.

The operation is as follows: When this apparatus is employed independently of a stove or range, it is understood that the pipes J and K are not employed. In operation the drain-pipe L is of course closed and the water entering from the pipe D fills the heating-chamber and water system. The burner-flame is directed primarily against the bottom of the chamber E and thereafter passes around and over the chamber, being confined by the hood N, and thence into the flue C. The products of combustion can be suitably conducted from the top of the flue C, if necessary, although the combustion will be such that such expedient may not be necessary. It is thus seen that the chamber E first utilizes the heat units and that the heated gases

passing under the flue the same are further absorbed by the water within the pipe G and the tank A, as is evident. The water circulates upwardly from the chamber E through the pipe G, and thence to the upper end of the tank A, and from the bottom of said tank through the pipe F into the chamber E, while the consumption of hot water and supply of cold water takes place in the usual manner.

10 It is evident that a device of this kind can be employed whenever it is necessary and independently of any other source of heat than the burner itself and that it can be located at the most convenient point and without reference to a stove or range.

15 It will thus be seen that by extending the pipe D into the tank A in the manner described and by making a connection from the outlet-pipe G to the top of said tank and from the bottom of the latter to the laterally-extending heating-chamber E, I make provision for a positive upward circulation in the pipe G and a downward circulation in the tank, said downward circulation causing the 20 water leaving the bottom of the tank to pass through the pipe F upward into the heating-chamber E, the effect of which is evident.

25 The advantages of such a structure are manifest—for instance, in warm weather—as it obviates the necessity of maintaining a fire 30 in a stove or range for the purpose of obtaining hot water. As above referred to, how-

ever, the device can be used in connection with a stove or range without material change in structure—for instance, by employing the 35 branch pipes J and K, leading to and from the range and communicating, respectively, with the pipes H and F. When thus communicating with the heating apparatus of the stove, the burner N may be used or dispensed 40 with, as found desirable.

Having thus described my invention, what I claim as new, and desire to secure by Letters Patent, is—

45 In a water-heater, a tank having inlet and outlet ports and an upright flue, a water-holding heating-chamber of greater area than said flue situated below said tank and communicating with the upper end thereof by means of a pipe passing through said flue, 50 the lower end of said tank communicating with said chamber, a burner situated below said heating-chamber, a hood surrounding said heating-chamber and having an open upper end forming a close joint from the bottom of the tank around said flue and a depending flange extending between the bottom of the tank and the top of the heating-chamber and provided with openings.

HENRY HARBECKES.
